UNITED STATES PATENT OFFICE.

SAMUEL B. WILLIS AND WILLIAM G. WILLIS, OF NEW YORK, N. Y.

SUBMARINE SPAR-NET SHIELD.

1,260,843.

Specification of Letters Patent. Patented Mar. 26, 1918.

Application filed June 23, 1917. Serial No. 176,863.

To all whom it may concern:

Be it known that we, SAMUEL B. WILLIS and WILLIAM G. WILLIS, both citizens of the United States, and residents of the city of 5 New York, borough of Manhattan, in the county and State of New York, have invented a new and Improved Submarine Spar-Net Shield, of which the following is a full, clear, and exact description:

10 Among the principal objects which the present invention has in view are: to provide obstructions which may be placed in the path of an attacking submarine; to prevent the submarine following in the wake 15 of an escaping vessel; to protect the vessel from torpedo attack; to provide means for preventing torpedoes striking the hull of a vessel when the attack is directed against the broadside of said vessel; and to provide 20 safety devices which after being used for the attainment of the primary objects, may be used as traps for submarines.

Drawings.

25 Figure 1 is a diagrammatic view employed for showing the method of operating with shields constructed in accordance with the present invention;

Fig. 2 is a side view of a shield constructed and arranged in accordance with the present invention;

Fig. 3 is a top plan view of the same.

Description.

35 As seen in the drawings, a plurality of light metal plates 8 are pivotally attached to a solid wooden spar 9 of suitable length and flotation power. The spar 9 is weighted by the plates 8, net 10, and weights 11 carried thereby so that the spar 9 is fully submerged to a depth equal to the netting 12, which is supported above the spar by short stanchions 13. The net 10 is suitably connected to the plates 8 and is constructed of any suitable material such as light metal bars 14. The bars 14 are united at the bottom to a spreader 15, which has pivotally attached thereto a series of weights 11. As indicated, the weights 11 are gaged to regulate the submersion of the spar 9. The net is maintained in its outspread relation by curved shield plates 16. The plates 16 are curved as shown best in Fig. 3 of the drawings, and are flexibly held by lines 17, 18 and 19. The lines 19 are attached to the ends of the spar 9 and in this manner sup-

port the upper ends of the plates 16, as seen best in Fig. 2 of the drawings.

The spars 9 and structures attached thereto may be carried on the deck of a ship. When the ship approaches a danger zone, the spars are suspended by davits out from the broadside of the ship, being there held by suitable lines and ready to be cast loose.

In the event of a torpedo attack being made against the side of the vessel, one or more spars equipped with the plates 8 and net 10, shield 16, and netting 12, are released at the side of the vessel, in the path of the oncoming torpedo.

In practice, the course of the ship is immediately changed, as indicated by the dotted line terminating in an arrow in Fig. 1. As soon as the vessel passes behind the spar and net which has been launched, it will be seen that the vessel is protected from a second torpedo attack and is ready to run from the pursuing submarine.

Should the submarine attack with shell fire or start in pursuit, the vessel continues a zigzag course as indicated in Fig. 1, and having turned the other side toward the submarine, a second spar with its equipment is dropped. Care is exercised to place the second spar in the general line of the flight of the ship, and so as to overlie the outer end of the first spar in the side path of the ship. The ship is again turned on its course, running now behind the two spars, which have been launched, while a third spar is provided on the side of the vessel, from which the third spar is launched.

When the course of the ship is placed so that the third spar may be launched, care is exercised to place the same at the extreme of the path of the vessel at the opposite side. In this way, it will be seen that the spars are so disposed that a pursuing submarine is compelled to pass around the spars or is endangered by hitting the same.

If the pursuit is continued, a fourth and a fifth spar may be launched, each time widening the path in the wake of the ship. It will be understood that any number of spars within reason may be carried and launched in moment of danger.

As each of the spars is launched, the shield plates 16 operate to straighten said spars to extend the same together with the net carried thereby, across the lines parallel to the course of the ship being pursued or attacked.

If the attack is suspended and the spar nets be undisturbed, it is evident that the nets 10 hanging below the surface of the water to a desired depth offer an entanglement to 5 submarines which may be operating in the vicinity where said nets have been placed.

Claim.

A shield as characterized comprising a 10 spar float; impact members suspended therefrom; means for maintaining said members vertically disposed, said means embodying a

net pendent from the lower edge of said members; means for regulating the submergence of said float, said means embodying a 15 submarine net trap pendent from said float, and weighted members pendent from the lower edge of said net; and means for maintaining the spread relation of said net, said means embodying inclined shield plates 20 flexibly connected with the lower edge of said net and supported by said spar float.

SAMUEL B. WILLIS.
